UNITED STATES PATENT OFFICE.

MARK W. DEWEY, OF SYRACUSE, NEW YORK, ASSIGNOR OF TWO-THIRDS
TO EMIL LAASS AND CHARLES H. DUELL, OF SAME PLACE.

ELECTRIC TELEGRAPHY.

SPECIFICATION forming part of Letters Patent No. 394,960, dated December 25, 1888.

Application filed November 21, 1887. Serial No. 255,695. (No model.)

To all whom it may concern:

Be it known that I, MARK W. DEWEY, of Syracuse, in the county of Onondaga, in the State of New York, have invented new and 5 useful Improvements in Electric Telegraphy, of which the following, taken in connection with the accompanying drawings, is a full, clear, and exact description.

The object of this invention is to expedite 10 the transmission of messages by the multiplex system of telegraphy; and it consists in the combination, with multiplex lines, of transmitting-keys arranged to be operated by one operator at one end of the said lines and 15 recording-levers at the opposite end of the lines and arranged with their markers in a row at right angles to the line of travel of the paper to print simultaneously side by side the several marks representing a letter or character, all as hereinafter more fully described, 20 and specifically set forth in the claims.

In the common transmission of signals through a telegraphic circuit it is well known that, with the exception of two letters, both 25 with the needle and Morse systems, it is necessary to depress the keys several times in order to transmit a single letter or signs representing it, the signs being composed of dots and dashes or the inclinations of a needle to 30 the right and left by making short and long contacts of the keys in the Morse system and depressions of right and left keys in the needle system. This consumes a great deal of time, and a small amount of business occupies 35 a single circuit continually and necessitates the employment of several wires or duplexing or quadruplexing one wire. In both cases mentioned several operators are required, according to the number of communications carried on, for the speed of the operator is not increased—*i. e.*, it takes one as 40 long to transmit a message on a diplex or quadruplex system as it does on a single circuit, and the gain, though great, is simply in 45 arranging apparatus at the terminal stations so that several operators may be able to communicate simultaneously over the same line. My invention carries it still farther, making it possible for one operator to do the work of 50 four in one direction in the same length of time, using two diplex lines, or one can send

a message in one-fourth or one-fifth of the time occupied in sending by the other method.

In the Morse and international alphabets the letters that occur the oftenest in transmitting are indicated by a fewer number of depressions of the key, in order to get as great speed as possible. The letters e and t, occurring oftener than others, are represented by a dot and dash, respectively, the two shortest signs used. The other letters and marks are made in the time that would be occupied in making from two to eight such simple signs. 55

In my invention the several marks required to represent a single letter are all made simultaneously, and consequently said letter is printed as quickly as a letter represented by a single mark, the aforesaid arrangement requiring an entirely new telegraphic code, which constitutes the subject-matter of another application for patent which I am about 60 to make. 65

For a more ready understanding of my present invention, however, I may here state that said code consists in printing in a row at 75 right angles to the line of travel of the paper the several marks representing a single letter or character, the marks in each row being of corresponding lengths, and the letters or characters being distinguished from each other by 80 the lengths of the marks and the distance of the marks from the longitudinal edges of the paper. Although messages could be transmitted by the code with a separate line-wire to each transmitting-key, yet to obviate the 85 use of the numerous wires and to expedite the operation, I employ two diplex or quadruplex lines, as hereinafter described.

Referring to the drawings, Figure 1 shows an exemplification of the use of my improved 90 code in printing the word "telegraph," and illustrates a general plan of the transmitting apparatus at one terminal station and recording apparatus at the other terminal of two diplex circuits. It is obvious, however, that 95 in order to communicate in both directions at the same time it is only necessary to combine this apparatus with any one of the several known systems of simultaneous transmission in opposite directions. The only difference 100 from the general plan, as will be seen by the drawings, is in the arrangement of the keys,

so that one operator may use all the keys in transmitting a message, and in the recording-levers, so that the message may be recorded on one strip of paper or other material provided for the purpose by the movement of all the levers. Fig. 2 is a diagram of a local circuit with two keys. Fig. 3 is a side elevation of the receiving and recording instrument, and Fig. 4 is a plan view of a modification of the transmitting-instrument adapted to be employed in connection with the diplex circuits.

It will be understood that precisely the same effect is produced on the recording-levers by the manipulation of the keys as when each key and corresponding recording-lever is operated by an individual operator, so it will not be necessary to explain the operation of the system, the mode of operation of which is so well known, but will proceed directly to describe my improved arrangements in connection with it.

The keys K' K^2 K^3 K^4 correspond with recording-levers R' R^2 R^3 R^4 , and when one or more of the keys are depressed the corresponding levers bring their pens or markers in contact with the paper P . The mark or marks made simultaneously on the paper strip to represent a letter are either composed entirely of dots or short dashes made by very short depressions of the keys and recording-levers or dashes made by longer depression of the keys and recording-levers, so that a letter is composed either of a dot or combination of dots, or a dash or combination of dashes made simultaneously, arranged across a strip of paper which moves in the direction indicated by the arrow in the drawings and between markers and a cylinder rotated by clock-work or some other means, said cylinder supporting the paper to receive the impressions from the markers, the latter being arranged side by side in a row at right angles to the travel of the paper, and thus when two or more markers make impressions simultaneously said impressions will be likewise in a row at right angles to the travel of the paper.

The marks on the strip of paper P represented the word "Telegraph." The letters are condensed as closely as letters printed on a type-writer, whereby a great deal comes under the eye at a glance, and the paper strip is thereby shortened to a more convenient length.

It will be noticed that the letters "g" and "p" are made by dashes and the other letters by dots.

The four keys, though they may be operated by both hands, are intended to be operated by the thumb and first, second, and third fingers of right hand. Now, these keys may be duplicated—*i. e.*, each local circuit may contain two keys, as shown in Fig. 2 of the drawings. The second set of keys may be arranged to be depressed by fingers of the left hand, the keys for both thumbs being in one

local circuit control one transmitter, the keys for the first finger of each hand being in another local circuit, another transmitter, &c. In this way the speed may be increased, for the sets of keys may be used alternately. While one set of keys is being released by one hand that has transmitted a letter the other set of keys may be operated by the other hand to transmit a letter.

The operation of one diplex line is substantially the same as fully described in a work entitled *Electricity and the Electric Telegraph*, sixth edition, by George B. Prescott, 1885, pages 866 to 869, inclusive, viz:

First. Keys K' and K^2 both open. In this position the entire battery is in circuit, sending to the line a negative or $-$ current of $-B - 3B = -4B$.

Second. Key K' open and K^2 closed. In this case battery B only is in circuit, sending to the line a negative or $-$ current of $-B$.

Third. Key K' closed and K^2 open. The entire battery is again in circuit; but in this case with the positive or $+$ pole to the line sending a current of $+3B + B = +4B$.

Fourth. Key K' and K^2 both closed. In this position the battery B only is in circuit, sending to the line a positive or $+$ current of $+B$.

Thus it will be understood that the line is caused to assume four distinct electrical conditions, corresponding with the four possible positions of the keys at the transmitting-station.

The receiving apparatus consists of two recording-levers, L' and L^2 , which are controlled by relays R' and R^2 . The construction of R' is in fact simply a polarized relay capable of responding to positive and negative currents. The relay R^2 differs materially from the relay R' in the arrangement of its local-circuit connections, by means of which the recording-lever L^2 is operated.

The normal position of the apparatus when neither key at the transmitting-station is depressed is that shown in the diagram.

The manner in which the relays R' and R^2 operate in each of the four electrical conditions of the line mentioned, so as to cause the recording-lever L' to respond solely to movements of key K' , and the recording-lever L^2 in like manner to the movements of key K^2 , and both in response to a simultaneous depression of key K' and K^2 , will be understood by reference to the following explanation:

First. K' and K^2 both open. A negative or $-$ current from both batteries. ($-4B$) The local circuit of recording-lever L' is kept open because the polarity of the line-current tends to hold the armature h of relay R' on its back-stop p . The local circuit of recording-lever L^2 is also open between armature j and lever r , because the current on the line is sufficiently powerful to overcome the spring r' and hold armature j against stop o . Thus recording-lever L^2 remains inactive.

Second. K' open and K^2 closed. A nega-

tive or — current from battery B only (— B.) The local circuit of recording-lever L' remains open between stop p' and armature h, because the polarity of the current is such as to hold 5 the latter against stop p. The action of this current upon relay R² is to cause the armature j, assisted by spring r', to move to the left and make contact with the lever r, but not with sufficient force to overcome the re- 10 tractile spring q', thus leaving armature j in a central position between stops o and o', thereby closing the local circuit and operating recording-lever L².

Third. K' closed and K² open. A positive 15 or + current from both batteries (+ + B.) This current causes the armature h of relay R' to move to the left, thus closing the local circuit at stop p' and actuating recording-lever L'. The armature j of relay R² is also 20 strongly attracted toward the left, pressing against the yielding lever r with sufficient force to overcome the spring q' and press the former against the stop o', thus opening the local circuit of recording-lever L².

25 Fourth. Keys K' and K² both closed. Positive or + current from battery B (+ B.) Relay R', which is arranged to close its local circuit by positive current of any strength, actuates the recording-lever L' precisely as 30 in the third case. The current upon the line in this case is not of sufficient strength to hold the armature j of relay R² against the stop o'. Consequently it moves together with lever r, assisted by spring q', to a central position, 35 thus closing the local circuit between armature j and stop q, through lever r, thereby operating recording-lever L². When armature j of relay R² passes directly over from one extreme position to the other—for example, from stop o to o'—it will be observed that 40 the local circuit is closed for an instant, but not long enough to produce any effect whatever upon the lever L². The other diplex line is operated in substantially the same 45 manner.

With the four transmitters fifteen letters can be made by a dot or a combination of dots, and the remaining eleven letters, short and, (,), period, and comma are made with a 50 dash or combination of dashes. The remaining sign, composed of four dashes, may serve to precede and follow the same signs when figures and other signs are intended instead of letters.

55 It is obvious from the above that the operator's ability to manipulate the keys is the only limit to the speed of the system, and a message may be received in the absence of the receiving-operator.

60 An inked ribbon may be used instead of pen and pencil for markers, operating similar

to that of a type-writer, or the markers may emboss or write with ink the same as other telegraphic ink-writers.

It will be understood that it is not necessary to use the apparatus in the precise arrangement shown, as any form of diplex apparatus may be used for the same purpose; and it is also obvious that in order to operate contraplex it will only be necessary to employ ordinary quadruplex apparatus in connection with each line.

The transmission of messages can be greatly facilitated and expedited by substituting for the keys K' K² K³ K⁴ elastic fingers I' I² I³ I⁴, 75 resting with their free ends upon a suitable metallic support, a, which is connected with the local circuits by wires c c c, as shown in Fig. 4 of the drawings. A ribbon, d, of paper or other insulating material is made to pass 80 by any suitable and well-known means, between the support a and fingers I' I² I³ I⁴, which ribbon has perforations b b of different lengths and arranged in different relative positions and representing the telegraphic 85 letters or characters to be transmitted. During the passage of said ribbon over the support a the solid portions of the ribbon, which become interposed between the fingers and support, break the circuits, the perforations 90 closing the circuits and producing the electric impulses according to the lengths and positions of the perforations.

Having described my invention, what I claim is—

1. The improved system of electric telegraphy consisting, essentially, of multiplex lines, transmitting-keys arranged to be operated by one operator at one end of said lines, and recording-levers at the opposite end of the 100 lines, and arranged with their markers in a row at right angles to the line of travel of the paper to print simultaneously side by side the several marks representing a letter or character, as set forth.

2. The combination of two diplex or quadruplex lines, manipulative keys arranged to be operated by one operator at one end of said lines, and recording-levers at the opposite end of the lines, and arranged with their 105 markers in a row at right angles to the line of travel of the paper, substantially as described and shown, for the purpose specified.

In testimony whereof I have hereunto signed my name, in the presence of two witnesses, at 115 Syracuse, in the county of Onondaga, in the State of New York, this 18th day of November, 1887.

MARK W. DEWEY. [L. S.]
